UNITED STATES PATENT OFFICE.

SAMUEL S. WILLIAMSON, OF PHILADELPHIA, PENNSYLVANIA, ASSIGNOR TO MARY P. WILLIAMSON, OF PHILADELPHIA, PENNSYLVANIA.

FLUSH SIPHON.

Application filed April 6, 1922. Serial No. 550,086.

My invention relates to new and useful improvements in flush siphons, and has for its object to provide a simple and effective device of this description which may be 5 readily secured within a flush tank and be so operated as to draw the water therefrom down to a given level and then automatically shut off and remaining inactive until the water has reached a given high level within 10 the tank before it can be again put into action.

A still further object of my invention is to provide a dasher for giving the water an initial lift or throw which will carry a certain amount thereof from the short leg of 15 the siphon to the long leg thereof to start the siphonic action, said dasher being so constructed and arranged that it will swing from two centers.

20 A still further object of my invention is to so construct a siphon that it may be cast of a single piece including the spud and dash chamber.

With these ends in view, this invention 25 consists in the details of construction and combination of elements hereinafter set forth and then specifically designated by the claims.

In order that those skilled in the art to 30 which this invention appertains, may understand how to make and use the same, I will describe its construction in detail, referring by numerals to the accompanying drawing forming a part of this application, in 35 which:—

Fig. 1, is a vertical section of the siphon showing the dasher in the position it normally assumes when the siphon is inactive.

Fig. 2, is a front elevation of the device.

Fig. 3, is a bottom plan view.

Fig. 4, is a section at the line 4—4 of Fig. 1.

Fig. 5, is a diagram showing the second position to which the dasher is swung when operated to put the siphon in action.

Fig. 6, is a view similar to Fig. 5 showing the dasher in its third position which it assumes after the siphonic action has been started and the lift lever released.

Fig. 7, is a view similar to Fig. 5 showing the dasher in the fourth position which it approximately assumes while water is flowing at less than full capacity through the siphon.

Fig. 8, is an enlarged bottom plan view of

the dasher, a portion thereof being broken away to show the manner in which the bail is attached.

Fig. 9, is an edge view of the dasher.

In carrying out my invention as here embodied, 1 represents the threaded spud which is intended to pass through a suitable hole in the bottom of the tank as is well understood and this spud has a flange 2 formed therewith to seat upon a suitable gasket or washer placed between it and the bottom of the tank to prevent leakage at that point.

With the upper portion of the spud is cast the long leg 3 of the siphon and this leg is curved the inner wall thereof describing a circle from a center which coincides with the pivot point 4 of the dasher for the purpose hereinafter set forth.

The upper portion of the leg 3 of the siphon extends upward at an angle to the curved portion thereof and is enlarged to form the choke pocket 5 with which the short leg 6 communicates, said short leg being cast throughout its length integral with the long leg and has formed therein the dasher compartment 7 in which the dasher 8 is adapted to swing.

9 represents an offset formed with the front wall of the short leg 7 and the upper wall of this offset is inclined as indicated at 10 to form a crotch in which the heel 11 of the dasher may seat and which also provides the pivot point 4 upon which the heel of the dasher rocks.

The dasher 8 is preferably made of a single piece of sheet metal having the portion 12 thereof bent backward upon itself and terminating in a semi-circular housing 13 in which the ends 14 of the wire bail 15 are pivoted. This bail 15 has the downwardly 95 extending sections 16 intended to extend within the dasher compartment 7, the sections 17 intended to extend upwardly upon the outside of the siphon and these last named sections are connected by the horizontal sections 18 with the loop 19 by means of which the bail may be attached to the lift lever 20 through a suitable link 21.

22 represents a stop to limit the downward swinging movement of the dasher and 23 are 105 flanges for limiting the downward sliding movement of said dasher for the purpose hereinafter explained.

When the siphon is properly placed with 110 in a flush tank and the bail connected to the

lift lever 20 the operation will be as follows:—

While the siphon is inactive the cross sections 18 of the bail will rest within the horn 5 24 projecting from the front wall of the siphon and the dasher will hang in the position shown in Fig. 1, the heel thereof bearing upon the pivot point 4 and the weight of 10 said dasher being supported by the bail it being preferable that the outer end of the dasher does not contact with the stop 22. When the handle or other operating mechanism is actuated to elevate the lift lever 20 the bail will be drawn upward which movement will swing the dasher upon the pivot point lifting the water within the compartment 7 and forcing the same from the high 15 water level indicated in Fig. 1 through the crown over the upper edge of the partition 25 20 thus suddenly filling the choke pocket 5 which will start the siphonic action at the point of outlet from said pocket and this initial siphonic action will continue to draw water from the tank until the long leg 3 has been 25 filled and the water flowing downward through the same is choked at the point 26 by the sudden change of the direction of flow before entering the spud. When this has been accomplished the siphonic action 30 will continue until the level of the water in the tank falls below the mouth of the short leg or the opening to the compartment 7 when an entrance of air at this mouth will automatically break the siphonic action. 35 When the dasher is swung from the position shown in Fig. 1 to the position shown in Fig. 5 by the lifting of the bail as just described the flow of the water upward through the compartment 7 will hold said dasher in 40 a vertical position but the release of the lift lever will permit said dasher to slide downward while remaining in this vertical position until the heel thereof comes in contact with the flanges 23, as shown in Fig. 6, when 45 the further downward movement of the bail will cause the dasher to assume approximately the position shown in Fig. 7 where it will remain until the siphonic action has ceased when it will swing to the position of normal rest shown in Fig. 1.

The purpose of this swinging of the dasher upon two centers and the sliding downward thereof is to permit it to return to its 50 normal position of rest without undue resistance of the water through which it must pass and further to provide for a second, third or greater number of actuations of said dasher for starting the siphonic action should the first actuation of said dasher not bring about the flow of water to the full capacity of the siphon as for instance should the first actuation of the dasher deliver only sufficient water to the choke pocket 5 to start the siphonic action to a less degree than 55 the full capacity of the siphon the release

of the lift lever will permit the dasher to assume the position shown in Fig. 7 and if the flow of water through the siphon say is one-half its capacity the outer end of the dasher will swing to a relatively low position so that by again actuating the lift lever the heel of the dasher will be drawn into the crotch 10 and the outer edge thereof brought into close proximity to the curved wall of the compartment 7 and then swung upward 70 so as to deliver a further supply of water to the choke pocket and establishing a full flow. This operation may be repeated as often as necessary to establish this full flow. 75

In practice I prefer to make the interior 80 of the siphon of greater width than the interior of the spud so that as the column of water flowing downward through the long leg 3 reaches the point of entrance to the spud it will be crowded toward the center 85 to gain access to said spud thus making an effectual choke at this point which I have found by experiment greatly increases the sensitivity of the siphon thereby increasing the readiness with which the siphonic 90 action takes place and continues.

The inclined wall of the crotch 10 serves to effect the proper seating of the heel of the dasher upon its pivot point when the dasher swings from the position shown in 95 Fig. 7 to the position shown in Fig. 1, by causing the heel of said dasher to slide up said incline thereby preventing the outer edge of said dasher from contacting with or bearing against the curved wall of the compartment 7. 100

Of course I do not wish to be limited to the exact details of construction as herein shown as these may be varied within the limits of the appended claims without departing from 105 the spirit of my invention.

Having thus fully described my invention, what I claim as new and useful is:—

1. In a siphon of the character described, a long leg and a short leg cast integral, the 110 wall dividing the interior of said legs being curved to form a dasher compartment, a dasher slidably pivoted within said compartment so that when swung upward its outer edge will travel in close proximity to 115 said curved wall, and when released will slide downward while maintained in its vertical position, and means for swinging the heel of said dasher to its normal pivot point at a predetermined point in its downward 120 movement.

2. In a siphon of the character described, a dasher compartment having a curved wall, a pivot point at the center of the curvature of said wall, a dasher the heel of which 125 is adapted to rock upon said pivot point, means for swinging said dasher upward to a vertical position, and when released will slide downward while remaining in a vertical position, and means for swinging said 130

dasher from out of its vertical position at a predetermined point in its downward movement.

3. In combination with a siphon of the character described, a dasher consisting of a single piece of sheet metal, a portion of which is bent backward upon itself and terminating in a housing, said dasher having a heel for loosely pivoting the same, and a 10 bail formed of a single piece of wire the ends of which are pivoted within said housing.

4. A flush siphon including a dasher compartment and a dasher having a changeable fulcrum located within said compartment.

15 5. A flush siphon having a dasher compartment in which are located two fulcrum points, one above the other, and a dasher so suspended as to be capable of an upward swinging movement about one fulcrum point, an endwise movement toward the second fulcrum point, a downward swinging movement about said second fulcrum point and a teeter movement to return it to the first mentioned fulcrum point.

20 6. For use in a flush siphon having a dash-

er compartment, a dasher fulcrumed in said compartment, and a bail pivoted to said dasher, said bail extending downwardly from the dasher to below the lower edges of the dasher compartment; two sections of 30 the bail turning in U-shape around said edges, and then extending upwardly outside of said compartment for connection with the actuating mechanism.

7. A flush siphon including a long and a 35 short leg with a dasher compartment in the latter, a dasher pivoted intermediate its length providing long and short free ends, means within the dasher compartment to provide two separate fulcrum points for the 40 shorter end whereby said dasher will swing about one fulcrum during its upward movement and about the other during its downward movement, said dasher swinging on its point after a portion of its downward movement has been made.

45 In testimony whereof, I have hereunto affixed my signature.

SAMUEL S. WILLIAMSON.
